UNITED STATES PATENT OFFICE.

ARTHUR ATWATER KINET, OF ARDMORE, PENNSYLVANIA.

VACUUM-TUBE UNIT.

Application filed April 28, 1928. Serial No. 683,358.

My invention relates to vacuum tube units comprising in combination holders or sockets for vacuum tubes, such as audions or the like utilized in radio and similar systems, and rheostat structure.

My invention resides in structure of the character hereinafter described and claimed for effecting a unitary and compact arrangement.

10 For an illustration of one of the various forms my invention may take, reference is to be had to the accompanying drawings, in which:

15 Fig. 1 is a top plan view of apparatus embodying my invention.

Fig. 2 is a vertical sectional view, parts in elevation, taken on the line 2—2 of Fig. 1.

20 Fig. 3 is a vertical sectional view, some parts in elevation, taken on the line 3—3 of Fig. 1.

Fig. 4 is an inside plan view of a structure shown in Fig. 3, with the bottom plate removed.

25 Fig. 5 is a fragmentary vertical sectional view, partly in elevation, taken on the line 5—5 of Fig. 1.

Fig. 6 is a fragmentary top plan view, partly in section, of structure shown in Fig. 1 with the rheostat knob removed.

30 Fig. 7 is an inside plan view of the rheostat knob.

Fig. 8 is a perspective view of the movable rheostat contact member.

35 Fig. 9 is a fragmentary sectional view, partly in elevation, taken on the line 9—9 of Fig. 4.

Fig. 10 is a diagrammatic view of one of the circuit arrangements in which the apparatus is utilizable.

40 Fig. 11 is a vertical cross sectional view of a modified form of my invention utilizing a different type of tube holder or socket.

Fig. 12 is a bottom plan view of the same with the bottom cover removed.

45 Referring to the drawings, 1 is a hollow base or housing, preferably of molded insulating material, as condensite, Bakelite or the like, having the integral cover or end closure 2 and the foot flange 3 provided with integral ears or lugs 4, by which the structure may be attached to any suitable support. Integral with the member 2 are the annular ribs 5 and 6, spaced from each other to form an annular groove or channel 7 in which is disposed the preferably bare helical resistance wire or conductor R, whose

ends extend downwardly through holes 8 in the member 2 to the inside of the housing structure. Secured to or integral with the member 2 is the upstanding lug or stop 9. The cap, knob or handle 10, preferably of molded insulating material of the character above referred to, and preferably having on its outer side the grip-forming ribs 11, has a downwardly extending circular flange 12, thereby forming a hollow cap or cup-like structure whose diameter, in the example illustrated, is substantially the same as the diameter of the aforesaid upstanding rib 5.

Molded in the member 10 is the stub shaft 13, which extends through a circular hole

in the member 2 and terminates within the housing or chamber 1 and has adjacent its end the circular groove 14, in which engages the forked end 15 of the sheet metal contact 16, or connector 16, whose forked end is biased for movement downwardly, as viewed in Figs. 2 and 3, to exert a downward bias upon the stub shaft 13, and therefore upon the cap member 10. Secured upon the metal

shaft 13 is the rheostat contact member 17, whose outer end 18 bears upon the helical

resistance conductor R, which projects sufficiently above the inner rib or ring 6 for that purpose, the knob or cap 10 having the internal lug or abutment 19 against which the central portion 20 of the contact member 17 abuts. Extending downwardly inside of the cap 10 and integral therewith is the lug or stop 21 to a distance below the upper surface of the lug 9, whereby the lug 9 extends into the path of travel of the lug 21, the lugs serving as means for limiting the extent of rotation of the cap 10 and the attached contact 17. The cap 10 may be provided with any suitable indicating means

25 for indicating the position of the rheostat contact 17. In the example illustrated, the indicating means 22 is formed by a depression in the cap 10 filled with paint or other material of suitable color or appearance.

Preferably molded integral with the wall or end closure 2 is a frusto-conical member 23 having the bottom or end wall 24. Adjacent the intersections of the walls 23 and 24 are the four holes through which extend the terminal posts of the vacuum tube V, as of the audion or similar type, comprising a filament cathode, an anode, and a control electrode or grid, as well understood in the radio art. The tube V may have the base 25 re-

100

105

110

25

ceived within the annular rib 26 and abutting against the shoulder 27.

Disposed around the member 23 are four resilient sheet metal contact members 28, 29, 30 and 31 terminating adjacent the aforesaid holes and engaging endwise against the vacuum tube terminal posts 32, 33, 34 and 35, respectively. The posts 32 and 33 constitute the terminals of the filament or cathode of the tube V; the post 34 constitutes the terminal of the plate or anode, and the post 35 the terminal of the grid or control electrode. The contacts 28 to 31 inclusive are secured to the under side of the wall 2 by screw bolts 36.

Integral with the member 23 is the boss or lug 37 for holding, as by screw 38, the holder or bracket member 39 for supporting or holding in place any suitable auxiliary devices, as, for example, the condensers 40 and 41 and the grid leak resistance 42, all of which may be held together as a unit by binding straps or tapes 43. The upper side of the unit may abut against the lugs 44 on the under side of the cover 2 and integral therewith.

Carried by the cover 2 are binding posts in suitable number, for any suitable purpose. In the example illustrated, the binding post 45 serves in common for connecting the external batteries A and B supplying current, respectively, for the cathode or filament of the tube V and the plate or anode circuit thereof. The other input or grid terminal is at the binding post 46, between which and the grid contact 31 is inserted the usual grid condenser 41, the grid leak resistance 42 being connected between the contact 31 and the post 46. The positive terminal of the battery A may connect to the binding post 47, which connects by conductor 48 with the filament contact 29, the other filament contact 28 connecting with one terminal of the resistance R, the rheostat contact 17 connecting through the member 16 to the binding post 45, all as indicated in Fig. 10. The free end of the resistance R at 49 may extend through a hole in the cover 2 and be bound on the under side thereof in any suitable way. The positive terminal of the battery B is connected to the binding post 50, which may be of a type as indicated for connecting a plurality of telephones, as T, or other devices, whose other terminals may connect to the similar binding post 51, which may be connected by conductor 52 above the cover 2 with the binding post 53, which connects with the plate or anode contact 30. Beneath the cover 2 the condenser 40 may be connected with the posts 45 and 51, as indicated, thereby serving as a high frequency by-pass in the anode circuit for the telephone T or other instruments and the battery B.

The casing formed by the walls 1 and 2 may be closed by the closure member 54, of sheet metal or other suitable material, which

is held in place against the annular shoulder 55 by screws 56 threaded into the tapped holes in the lugs 57 molded integral with the wall 1.

Referring to Figs. 11 and 12, there is shown a modification of my invention utilizing another and standard form of socket or holder for vacuum tubes.

In the cover or end closure 2 is a circular or other suitably shaped aperture 58 within 75 and preferably concentric with the upwardly extending annular flange 59 molded integral with the cover 2. The metallic cylindrical shell 60 rests with the lower end against the cover 2 and fits within the flange 59, the 80 casing 60 having the usual bayonet slot 61, with which co-acts a pin upon the base of a vacuum tube for locking the same in the socket 60, as well understood in the art. The shell 60 has a plurality of lugs 62 extending through apertures in the cover 2 and bent outwardly or horizontally as indicated to hold the shell 60 in fixed position upon the cover 2, this structure being of the character disclosed in my prior application Serial No. 576,423. Secured upon the under side of the cover 2 with their ends projecting over the aperture 58 are the four resilient or yielding metallic contacts 63, 64, 65 and 66, secured by the screws 67 extending upwardly through the cover 2 and held by suitable nuts. The contacts 63-66 are in the form of leaf springs and preferably, as indicated in Fig. 11, each comprises a plurality of overlying ribbons or sheet members 100 or laminae. Integral with the cover 2 and projecting from the under side thereof are the posts or studs 68 serving suitably to position and space the contacts and to prevent their movement about their screws 67. With one of the contact members, as 64, is connected the biasing spring contact member 105 11 of the rheostat structure, as hereinbefore described, the contacts 64 and 65 engaging with the contact posts or studs on the end of the vacuum tube unit and forming terminals on the filament thereof. The contact 63 may engage the tube terminal which connects with the grid thereof, and the contact 66 may engage with the anode or plate terminal of the tube unit.

There may be disposed within the chamber or base 1, as hereinbefore described, the condensers 40 and 41 and grid leak resistance 42, all of which may be held together as a unit as hereinbefore described, the unit being held against the lugs 44 on the inside of the cover 2 by the bracket 39 secured by screw 38 to the lug 37, which in this instance is integral with the wall 1 and cover 2.

What I claim is:

1. A vacuum tube unit comprising a casing having an end closure, a frusto-conical tube-holding member carried by said end closure and projecting into said casing, a

lug integral with said member, and a supporting bracket secured to said lug.

2. A vacuum tube unit comprising a casing adapted to support a plurality of radio receiving elements thereon, a vacuum tube mounted in said casing having inclined edges for guiding said vacuum tube into operative position, and contacts on the opposite side of said mounting for engaging the electrodes of said tube.

3. A vacuum tube unit comprising a casing moulded insulating material having an integral end closure, said end closure adapted to support a plurality of radio receiving elements and having a depression therein form-

ing a mounting structure for a vacuum tube, and contacts on the opposite side of said depression for cooperating with the vacuum tube electrodes.

4. A vacuum tube unit comprising a casing having an integral end closure, said end closure adapted to support a plurality of radio receiving elements thereon, and a frusto-conical tube holding member carried by said closure and projecting into said casing.

In testimony whereof I have hereunto affixed my signature this 19th day of April, 1923.

ARTHUR ATWATER KENT.
